UNITED STATES PATENT OFFICE.

JOHN BROOKS AND WILLIAM SCULLY, OF DETROIT, MICHIGAN.

GEAR-CUTTER.

SPECIFICATION forming part of Letters Patent No. 276,346, dated April 24, 1883.

Application filed December 2, 1882. (No model.)

To all whom it may concern:

Be it known that we, JOHN BROOKS and WILLIAM SCULLY, of Detroit, in the county of Wayne and State of Michigan, have invented 5 a new and Improved Gear-Cutter, of which the following is a full, clear, and exact description.

Our improvements relate to machines for cutting beveled and straight spur-gearing and 10 worm-gearing.

The object of our invention is to provide a gear-cutter that can be used upon any lathe, or upon any machine provided with a pair of centers and a driving-pulley.

15 To these ends the invention consists in certain novel features of construction and arrangement, as hereinafter described and claimed.

Reference is to be had to the accompanying drawings, forming part of this specification, in 20 which similar letters of reference indicate corresponding parts in all the figures.

Figure 1 is a side elevation of our improved gear-cutter. Fig. 2 is a vertical section, and Fig. 3 is a plan view of the same. Fig. 4 is a 25 vertical transverse section at right angles to Fig. 2.

A is the base-plate.

B is the standard, fitted to slide upon the base-plate A.

30 D is the index-wheel, and C is a tubular socket-piece fitted within the standard B, and formed at its upper end with arms or flanges a a, that are provided with pins E, entering the index-wheel D.

35 F is a ring-shaped locking-nut screwed upon the upper end of the standard B, and projecting over the inner edge of the index-wheel D, so as to lock the index-wheel and prevent it from rising.

40 G is a screw passing through the bottom of the socket C and entering a recess in the inner side of the standard B, when the screw is fitted with a beveled pinion, K, engaging a similar pinion on a horizontal spindle, I, that is provided at its outer end with a hand-wheel, H, for operation of the spindle and the screw to raise and lower the socket C.

45 In the upper end of the socket C is to be placed a mandrel, b, as shown in Fig. 4, clamped 50 by a set-screw, c, and this mandrel carries the work, which is held in place upon the mandrel by a set-nut, d.

The base-plate A is provided with a screw-shaft, e, having a hand-wheel at its outer end for adjustment of the standard B lengthwise 55 of the base-plate. The standard B is beveled at f to support the index-wheel D, the object of this being to allow of the index-wheel being locked securely without jamming; and it also allows of ready adjustment for wear. 60

The socket C and the index-wheel are firmly connected together by the pins E, which act as drivers for the index-wheel, causing its perfect rotation with the gear being cut, and at the same time allowing of the socket being fed up 65 and down while cutting each tooth.

At one side of the index-wheel, and fixed to the standard B, is a slotted post, h, carrying the pin i, that enters the holes in the wheel.

70 k k are sector-plates connected by a slotted segmental plate, l, by means of screws that enter a groove, m, in the top of the index-wheel, so that the sector-plates are held firmly in position, and may be adjusted the proper distance apart for dividing any of the circles of holes 75 into any required number, their action being the same as the sector-arms used on ordinary index-plates.

In using the machine or tool the base A will be supported by the ways of the lathe, and the 80 base is provided with an apertured lug, p, for receiving the devices by which it is held in place. The cutter represented at q is upon an arbor, r, which is fitted to the lathe-center. For cutting beveled gearing the base A may 85 be attached to the lathe upon the ways by means of a bolt passing through the lug p, so as to allow of the base-plate being tipped at the angle required; and in cutting either beveled or worm gearing the blank may be fed 90 either against or under the cutter with a cross-screw, or at an angle with a vertical screw, whichever may be most convenient. This construction renders the machine complete, so that it may be used upon any ordinary lathe; but 95 if the lathe is provided with a saddle of ordinary character the base-plate A may be dispensed with and the attachment applied directly to the saddle.

Having thus described our invention, what 100 we claim as new, and desire to secure by Letters Patent, is—

1. In gear-cutters, the combination of the socket C, the pins E, and index-wheel D to-

gether and with the supporting-standard B, substantially as described, for operation as set forth.

2. In gear-cutters, the locking-ring F, combined with the index-wheel D and standard B, substantially as and for the purposes set forth.

3. In gear-cutters, the combination of the socket C, fitted for carrying the work, the adjusting-screw G, and beveled gearing K, substantially as described.

4. The combination of the standard B, ad-

justing-screw G, socket C, pins E, and index-wheel D, substantially as shown and described.

5. The combination of the standard B, formed with a conical or beveled surface, f, and the index-wheel D, beveled at its under side, as and for the purposes specified.

JOHN BROOKS.
WM. SCULLY.
